CLAIM

The ornamental design for a magnetic cell phone ring stand as shown and described.

DESCRIPTION

FIG. 1 is a front, right and top perspective view of a magnetic cell phone ring stand, showing my new design.

FIG. 2 is a rear, left and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is another front, right and top perspective view of the magnetic cell phone ring stand of FIG. 1 shown in another configuration of use.

FIG. 10 is another front, right and top perspective view of the magnetic cell phone ring stand of FIG. 1 shown in another configuration of use; and,

FIG. 11 is an enlarged view of detail 11 in FIG. 1.

The dashed broken lines depict portions of the magnetic cell phone ring stand that form no part of the claimed design. The dot-dash broken lines in FIGS. 1 and 11 depict the boundaries of the enlarged views and form no part of the claimed design.
